US00D962422S

(12) **United States Design Patent** (10) **Patent No.:** **US D962,422 S**
(45) **Date of Patent:** **** Aug. 30, 2022**

(54) **ORAL CARE DEVICE**

(71) Applicant: **Fresh Health Inc.**, Mountain View, CA (US)

(72) Inventors: **Ryan Christopher Evans**, San Francisco, CA (US); **Angela Junyan Chu**, San Francisco, CA (US); **Sophie Katherine Sheeline**, San Francisco, CA (US); **Michael Lee Hanuschik**, Mountain View, CA (US); **Jonathan Riley Cox**, Saratoga, CA (US); **Kristina Jenna Cook**, San Francisco, CA (US)

(73) Assignee: **FRESH HEALTH INC.**, Mountain View, CA (US)

(**) Term: **15 Years**

(21) Appl. No.: **29/754,397**

(22) Filed: **Oct. 9, 2020**

Related U.S. Application Data

(63) Continuation of application No. PCT/US2020/028311, filed on Apr. 15, 2020.

(51) **LOC (13) Cl.** **24-02**

(52) **U.S. Cl.** **D24/111**

(57) **CLAIM**

The ornamental design for an oral care device, as shown and described.

DESCRIPTION

FIG. 1 is a top perspective view of an oral care device. FIG. 2 is a front view of the oral care device of FIG. 1. FIG. 3 is a rear view of the oral care device of FIG. 1. FIG. 4 is a left side view of the oral care device of FIG. 1. FIG. 5 is a right side view of the oral care device of FIG. 1. FIG. 6 is a top view of the oral care device of FIG. 1. FIG. 7 is a bottom view of the oral care device of FIG. 1; and, FIG. 8 is a bottom perspective view of the oral care device of FIG. 1.

The broken lines showing oral care device elements are for the purpose of illustrating portions of the article that form no part of the claimed design.

1 Claim, 7 Drawing Sheets
